(57) **CLAIM**

The ornamental design for a scraper for a gel cup, as shown and described.

DESCRIPTION

FIG. 1 is a perspective view of a scraper for a gel cup showing my new design;

FIG. 2 is a side view thereof, the opposite side being a mirror image thereof;

FIG. 3 is a front view thereof, the opposite rear side being mirror image thereof;

FIG. 4 is a top view thereof;

FIG. 5 is a bottom view thereof; and,

FIG. 6 is a sectional view along the line 6—6 of FIG. 4.

The broken line showing of a gel cup is included for the purpose of illustrating environmental structure and forms no part of the claimed design.

1 Claim, 2 Drawing Sheets

FIG. 4

FIG. 6

FIG. 5
